FIG. 1

FIG. 2

FIG. 3

FIG. 4

FIG. 5

FIG. 6

FIGURE 1 is a view in perspective of a portable high chair, showing my new design;

FIGURE 2 is a side elevational view;

FIGURE 3 is a front elevational view of the high chair;

FIGURE 4 is a top plan view of the chair;

FIGURE 5 is a view in vertical longitudinal section of the chair; and

FIGURE 6 is a view in rear elevation thereof.

The dominant features of my design reside in those portions shown in full lines on the drawing.

The broken line showing of a table top fragment in FIGURE 2 is for illustrative purposes only.

The elevational configuration of the remote side of the chair would be the exact reverse of the elevation of the near side as shown in FIGURE 2.

This application is a continuation-in-part of my earlier filed application Serial No. D-82,569, filed November 12, 1964, and now abandoned.

I claim:

The ornamental design for a portable high chair, as shown and described.
